UNITED STATES PATENT OFFICE.

CHARLES W. MCCOY, OF SPOKANE, WASHINGTON, ASSIGNEE TO A. B. C. REFRIGERATOR CO., OF CHICAGO, ILLINOIS, A CORPORATION OF ARIZONA.

REFRIGERATOR.

Application filed March 25, 1918. Serial No. 224,413.

To all whom it may concern:

Be it known that I, CHARLES W. McCoy, a citizen of the United States, residing at Spokane, in the county of Spokane and State of Washington, have invented a certain new and useful Improvement in Refrigerators, of which the following is a specification.

This invention relates to refrigerators and has for its object to provide a new and improved device of this description. The invention has, among other objects, to provide a refrigerator for use in houses, stores, restaurants and the like, wherein a liquid refrigerant is used for cooling purposes, and this refrigerant is circulated through the compartment to be cooled without the use of a pump or motor. The invention is illustrated in the accompanying drawings where-

in—
20 Figure 1 is a front elevation of a refrigerator in part section embodying the invention.

Figure 2 is a side elevation in part section of the refrigerator shown in Figure 1.

25 Figure 3 is a horizontal sectional view through the receptacles containing the refrigerant material;

Figure 4 is a view of one form of actuating device for moving the receptacles containing the refrigerant.

30 Figure 5 is a plan view of the device shown in Figure 4.

Figure 6 is an enlarged view showing the rocking connection between the receptacles containing the refrigerant and the support therefor.

Like numerals refer to like parts throughout the several figures.

For purposes of illustration I have shown 40 my invention as applied to an ordinary refrigerator or ice box. In this construction there is a stationary box or casing 1 containing a compartment 2 in which is movably mounted a plurality of receptacles containing a refrigerant. In the construction shown there are four receptacles, 3, 4, 5 and 6. These receptacles may be located in any desired manner, but as shown are adjacent to each other and are separated by walls 7, 50 8, 9 and 10. The receptacles are preferably arranged in two pairs, 3 and 6 forming one pair, and 4 and 5 another pair. The recep-

tacles 3 and 6 are arranged so that the liquid refrigerant may pass in one direction from one to the other, but cannot return through the same opening. For this purpose I provide one or more valves 12 which may be of any form such as an ordinary check valve controlling one or more openings, the valves being arranged so that liquid can pass through the openings from receptacle 6 to receptacle 3 but cannot return. There are one or more communications between receptacles 4 and 5 which are controlled by similar valves 13 arranged to work in the opposite direction, that is, to permit liquid to pass from receptacle 4 to receptacle 5 but prevent such liquid from returning to receptacle 4. Receptacles 3 and 4 are connected by a pipe 14 and receptacles 5 and 6 are connected by a pipe 15. The receptacles are movably mounted in the casing or box so that they may be moved or rocked as herein shown. The receptacles are mounted upon pivots 16 carried by supports 17. Either the pivots or supports may be connected with the receptacle or the stationary compartment. The stationary compartment is provided with a suitable removable cover and the receptacles may also be provided with removable covers so that the refrigerant may be easily inserted or removed. The pipes 14 and 15 extend below the receptacles and into one or more compartments 18 and 19 to be cooled. The openings in the partition 21 are arranged to permit the necessary movement of the pipes when the receptacles are rocked. A suitable refrigerant is placed in the receptacles and any desired refrigerant may be used such as, for example, cold brine. The device, for example, can be used cheaply and efficiently by putting ice and brine in the receptacles or ice and salt to form brine. Some means is provided for moving the receptacles. As illustrated, I provide an actuating device connected with the receptacles and means for applying power to said actuating device to rock the receptacles. One convenient construction is shown which consists of a shaft 95 22 provided with a crank 23. This crank is connected by a connecting device 24 with the receptacles at any desired point, as, for example, at about the middle of the end at 25.

This connecting device passes through an opening 24^a in the casing or box. Power may be applied to shaft 22 and its connections in any desired manner. An efficient method is to place the shaft outside of the compartment and provide an arrangement so that when the door is open the shaft will be rotated to rock the receptacles. I have shown one form for doing this. In this construction the doors 26 are provided with suitable hinges and each door has a curved rack 27 illustrated in detail in Figures 4 and 5. This rack is struck from the center about which the door moves. The rack 27 connects with a pinion 28 on the shaft 22. When there are several doors some means is provided so that when one door is opened the pinions associated with the racks of the other doors will not prevent the rotation of the shaft 22. This may be done, for example, by leaving the ends 29 of the racks 27 free from teeth so that when the doors are closed the pinions will not engage the racks. By omitting the teeth from the ends of the racks the pinions are disengaged from the racks when the doors are shut, and this permits the receptacles to adjust themselves and come to a level after the doors have been opened and closed. One construction for securing this result is illustrated in Figure 4 where the pinion 28 engages the stop 30 on the shaft 22. A spring 31 is compressed between the pinion and the stop 32 so as to secure a frictional engagement. When the door is opened this frictional engagement is sufficient to permit the engagement between the rack 27 and the pinion 28 to rock the shaft. If any pinion, however, is engaged by the rack of a door that is not being moved, the pinion will be held still but the shaft will rotate in the pinion. Any other means for applying power to the shaft 22 may be used. Similar racks 27 and pinions 28 and shafts 22 and associated parts may be used with the other doors 33 and 34.

I have described in detail a particular construction embodying the invention, but it is of course evident that the parts may be varied in many particulars without departing from the spirit of the invention hereto attached and I therefore do not limit myself to the particular construction shown.

The use and operation of my invention are as follows:

When the device is in use the receptacles contain a liquid refrigerant material such, for example, as brine. The receptacles may also contain ice for keeping the brine cool. The liquid refrigerant of whatever nature used, passes into the pipes 14 and 15 which extend through the chamber or compartment to be cooled.

The liquid refrigerant is circulated through these pipes without the use of a

pump or motor, and hence without expensive apparatus for this purpose.

When power is applied to shaft 22 by opening one of the doors or in any other manner the shaft is rocked so as to move the receptacles about their pivotal points.

Referring now to Figure 2, if the receptacles are moved so that the tops thereof are moved to the right, the level of the liquid in receptacles 4 and 3 will be higher than the level in receptacles 5 and 6. The liquid will then flow by gravity through valves 13 from receptacle 4 to receptacle 5 but cannot flow from receptacle 3 to receptacle 6. This will cause the liquid to rise at a higher level in receptacle 5 than in receptacle 6 and the liquid will then flow through pipe 15 from receptacle 5 to receptacle 6. If, now, the receptacles are rocked in the opposite direction, the level of the liquid in receptacles 5 and 6 will be higher than the level of the liquid in receptacles 3 and 4 and liquid will flow from receptacle 6 to receptacle 3 but will not flow from receptacle 5 to receptacle 4. This raises the level of the liquid in the receptacle 3 above that in receptacle 4 and hence the liquid flows by gravity through pipe 14 from receptacle 3 to receptacle 4. As the receptacles are rocked it will be seen that this operation is repeated and that the receptacles and pipes provide a complete circulatory system. When power is applied to the shaft 22 by the doors, this rocking and circulation will occur every time the door is opened and closed. In view of the fact that the pipes 14 and 15 extend below the receptacles and into the compartment to be cooled, it will be seen that while the doors are closed there will still be a circulation, because as the refrigerant material absorbs heat from the compartment to be cooled, a portion thereof will rise in the upwardly extending portions of pipes 14 and 15 and the heavier cooler liquid will fall, thus producing a circulation which keeps the compartment at the proper temperature.

By having the receptacles 3, 4, 5, and 6 containing the refrigerant material insulated as herein shown, this circulation becomes exceedingly effective because this insulation prevents the heat from being absorbed except through the material in the pipes 14 and 15, and as the material in these pipes absorbs heat from the compartment to be cooled the heavier material sinks into them and the lighter heated material goes back to the receptacles and is recooled. These downwardly extending pipes extend through the compartment to be cooled so as to affect the temperature therein.

It will be noted that the receptacles or tanks for the temperature varying material have substantially horizontal and substantially vertical walls and that the pipes 14

each has a substantially horizontal portion in a different horizontal plane from the tanks and two substantially vertical end portions which communicate with the tanks 5 through the substantially horizontal walls, the substantially horizontal portions of the pipes passing through the receptacle or chamber to be cooled, and that these pipes have a siphonic action in transferring the 10 liquid from one tank to another when the levels of the liquid in the tanks are different so as to tend to equalize said levels. It will further be noted that there is means for positively delivering the temperature varying 15 liquid from one tank to another, this being accomplished by the movement of the tank by the motive power which drives the shaft 22 as for example when the door is opened or closed. This positive delivery or 20 movement of the liquid from one tank to another raises the level of the liquid in one tank and lowers it in the other and the pipes 14 act as siphons to return the liquid by siphonic action to the tank having the lower 25 level so as to tend to reestablish a common level in both tanks.

I claim:

1. A refrigerator comprising a compartment, a plurality of receptacles movably 30 mounted in said compartment and containing refrigerant material, means for connecting said receptacles, said receptacles and said means for connecting them forming a complete circulatory apparatus containing 35 the refrigerant to be circulated, an actuating device connected with said receptacles, and means for applying power to said actuating device to rock said receptacles.

2. A refrigerator comprising a compartment, a plurality of receptacles movably 40 mounted in said compartment and containing refrigerant material, means for connecting said receptacles, said receptacles and said means for connecting them forming a complete circulatory apparatus containing 45 the refrigerant to be circulated, an actuating device connected with said receptacles, and means outside of said stationary compartment for applying power to said actuating device to rock said receptacles.

3. A refrigerator comprising a compartment, a plurality of receptacles movably 50 mounted in said compartment and containing refrigerant material, means for connecting said receptacles, said receptacles and said means for connecting them forming a complete circulatory apparatus containing 55 the refrigerant to be circulated, an actuating device connected with said receptacles, and a door for said stationary compartment by means of which access is 60 secured thereto, and a connection between said door and said actuating device whereby when the door is open power is applied

to said actuating device to rock said receptacles.

4. A refrigerator comprising a compartment, four receptacles in said compartment adapted to receive refrigerant material, said receptacles movably mounted therein, the 70 receptacles forming two pairs, valves for controlling the communication between the receptacles of each of said pairs, said valves permitting the refrigerant to flow in one direction but stop its flow in the other direction, and pipes connecting the receptacles of one of said pairs with the receptacles of the other pair, an actuating device connected with said receptacles and means for applying power to said actuating device to 75 rock said receptacles.

5. A refrigerator comprising a compartment, four receptacles in said compartment adapted to receive refrigerant material, said receptacles movably mounted therein, the 80 receptacles forming two pairs, valves for controlling the communication between the receptacles of each of said pairs, said valves permitting the refrigerant to flow in one direction but stop its flow in the other direction, and pipes connecting the receptacles of one of said pairs with the receptacles of the other pair, an actuating device connected with said receptacles, and a door 85 for said compartment by means of which access is secured thereto, and a connection between said door and said actuating device whereby power is applied to the actuating device to rock said receptacles when 90 the door is moved.

6. A refrigerator comprising a compartment, four receptacles in said compartment all of said receptacles being substantially in the same horizontal plane adapted to receive 100 refrigerant material, a compartment to be cooled, said receptacles having two pairs of valves for controlling the communication between the receptacles of each of said pairs, said valves permitting the refrigerant to flow in one direction but stop its flow in the other direction, a compartment to be cooled, pipes connecting the receptacles of one of said pairs with the receptacles of the other pair, said pipes extending downwardly 105 through the compartment to be cooled and back up to the receptacles.

7. A temperature varying apparatus comprising a compartment, a door for said compartment, receptacles adapted to contain temperature varying liquid in said compartment, a connection between said receptacles and means actuated by the door of the compartment for causing liquid to be transferred from one receptacle to the other.

8. A temperature varying device comprising two receptacles adapted to contain temperature varying material, means for positively delivering temperature varying

material into one of said receptacles and a return pipe communicating with the interior of both receptacles below the liquid level therein, said return pipe having a portion thereof in a different plane horizontally from said receptacles whereby said material is moved from the first mentioned receptacle to the other by siphonic action.

In testimony whereof, I affix my signature in the presence of two witnesses this 10th nineteenth day of March 1918.
